TEXTILE DRAWING MECHANISMS

Erwin Dausch, Esslingen, Neckar, Germany, assignor to SKF Kugellagerfabriken G. m. b. H., Schweinfurt, Germany

Application December 7, 1955, Serial No. 551,696

Claims priority, application Germany December 8, 1954

14 Claims. (Cl. 19—135)

The present invention relates to textile drawing mechanisms and more particularly to textile drawing mechanisms which include a set of top belts guided by a top belt cage and cooperating with a set of top rolls of the drawing mechanism.

In textile drawing mechanisms of this type the top belt cage is loosely connected to the top roll loading means and has a certain amount of play which sometimes results in improper alignment of the top belt cage with respect to the remainder of the drawing mechanism. Such improper alignment results in undesirable operation of the drawing mechanism.

One of the objects of the present invention is to provide a top roll loading means and a top belt cage which cooperate with each other in a manner which guarantees proper alignment of the top belt cage.

Another object of the present invention is to guarantee this proper alignment of the top belt cage while at the same time providing the top belt cage with the necessary freedom of movement with respect to the top roll loading means.

A further object of the present invention is to provide an arrangement where proper alignment of the top belt cage is assured and at the same time a spring for urging the top belt cage downwardly toward the drawing belt is unnecessary.

An additional object of the present invention is to provide an arrangement where the top belt cage cooperates with a saddle member of the top roll loading means in a manner enabling this saddle member and cage to retain the shaft of the top rolls cooperating with the saddle member in its operating position while at the same time guaranteeing proper alignment of the top belt cage.

Also, the objects of the present invention include the provision of a structure capable of accomplishing the above objects and at the same time being ruggedly and simply constructed and reliable in operation.

With the above objects in view the present invention mainly consists of a textile drawing mechanism which includes a top roll loading means provided with a saddle member. A top belt cage member cooperates with this saddle member, and a guide means is formed in part by the cage member and in part by the saddle member for guiding the cage member for turning movement with respect to the saddle member substantially about the axis of the top rolls which cooperate with the saddle member.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a fragmentary partly sectional side elevational view of a textile drawing mechanism including the structure of the present invention, Fig. 1 being taken along

2

line 1—1 of Fig. 2 in the direction of the arrows and being turned through 180° with respect to Fig. 2;

Fig. 2 is a view of the top rolls loading means and top belt cage of Fig. 1 as seen from the underside of Fig. 1;

Fig. 3 is a side elevational view of an arm of the top roll loading means which includes the saddle member of the present invention;

Fig. 4 is a sectional view taken along line 4—4 of Fig. 10 in the direction of the arrows;

Fig. 5 is a fragmentary perspective view of the saddle member according to the present invention;

Fig. 6 is a perspective view of the top belt cage member according to the present invention;

Fig. 7 is a sectional elevational view taken along line 7—7 of Fig. 1 in the direction of the arrows;

Fig. 8 is a fragmentary view illustrating the top belt cage of Fig. 1 in a position where the top rolls cooperating with this cage are adapted to be released;

Fig. 9 is a sectional elevational view corresponding to Fig. 7 of a different embodiment of the present invention;

Fig. 10 is a sectional fragmentary side elevational view of a third embodiment of the present invention;

Fig. 11 is a fragmentary side elevational view of another embodiment of the present invention;

Fig. 12 shows the structure of Fig. 11 in a different position; and

Fig. 13 is a fragmentary sectional view taken along line 30 13—13 of Fig. 11 in the direction of the arrows.

Referring now to the drawings, and to Fig. 1—8 which illustrate one embodiment of the invention, it will be seen that a top roll loading means includes the elongated channel member 1 which is open at its bottom and which is adapted to be located in a known manner or is adapted to be retained in the operating position indicated in Fig. 1 with a releasable catch mechanism or the like. The channel member 1 is provided with a pivot pin 3 which extends between its side walls, and an elongated member 2 is provided with downwardly extending lugs through which the pivot pin 3 extends, so that the member 2 is turnable upon the pivot pin 3, in the manner indicated in Figs. 1 and 2, the member 2 being located between the side walls of the channel member 1. The member 2 extends forwardly over the horizontally extending lower portion of a stop member 4 of substantially L-shaped cross section, as indicated in Fig. 1, so that when the member 1 is raised to an inoperative position, the downward movement of the member 2 will be limited by engagement with the stop 4.

The member 2 is provided with a pair of downwardly extending lugs 5 which carry a pivot pin 6 extending between these lugs 5, and an elongated arm 7 is pivotally carried by this pivot pin 6 in the manner indicated in Figs. 1 and 2. The member 7 is provided intermediate its ends with a pair of downwardly extending walls forming from the member 7 saddle member 8a. Adjacent its forward end the arm 7 is provided with a saddle member 9 formed by downwardly extending wall portions integral with the arm 7. The saddle member 8a cooperates with a set of top rolls 10 having their shaft engaged by the saddle member 8a in a well known manner, and a front set of top rolls 11 cooperates with the saddle member 9. Springs 12 cooperate with the channel member 1 and the arm 7 for urging the top rolls 10 and 11 downwardly, in the manner indicated in Fig. 1, when the channel member 1 is in the operating position indicated in Fig. 1, these top rolls 10 and 11 are cooperating with bottom rolls, in the manner indicated in dot-dash lines in Fig. 1.

The front wall of the channel member 1 is provided with an inwardly extending bottom flange 13 over which

a forwardly extending tongue 14 of the arm 7 is located, in the manner shown at the left end of Fig. 1, so that when the channel member 1 is raised to an inoperative position the tongue 14 will engage flange 13 to limit the downward movement of the arm 7.

In accordance with the present invention a guide means is provided for guiding the top cage member 16a shown most clearly in Fig. 6 for turning movement with respect to the saddle member 8a about an axis which may be the axis of the rolls 10 or an axis parallel to this axis. In the embodiments of Figs. 1-8, the top belt cage member 16 has the construction indicated most clearly in Fig. 6, and the pair of intermediate substantially vertical walls of the cage member 16 are located respectively next to the outer faces of the downwardly extending walls which form the saddle member 8a.

As is indicated in Fig. 5 as well as Fig. 4 and Fig. 3, the saddle member 8a is provided with a pair of arcuate cutouts in its bottom edge portions into which the shaft of the top rolls 10 extends, and at the outer side faces of the side walls of the saddle member 8a, the latter is provided with a pair of arcuate projections 15a having outer arcuate surfaces forming part of a circle extending about the axis of the top rolls 10 through approximately 180°. The cage member 16 is provided at its intermediate pair of side walls with arcuate cutouts 17a having the same configuration as the outer arcuate surfaces of the projections 15a and slidably engaging the latter, as indicated in Figs. 1 and 2, so that the cage member is in this way guided with the guide means constituted by elements 15a and 17a for turning movement with respect to the saddle member 8a about the axis of the top rolls 10. As is indicated in Fig. 7, the inner side surfaces 19a of the intermediate pair of walls of the cage member 16a are located closely adjacent to the outer side surfaces 18 of the saddle member 8a. Thus, with this arrangement the cage member 16a will be accurately guided by the saddle member 8a for turning movement with respect to the latter, and at the same time the cage member cannot become misaligned to provide undesired operation.

The cage member 16a includes a wall 20a formed with a notch 21 through which a screw member 22 freely extends, this screw member being threadedly connected to the arm 7 and having a bottom head end 23 of a diameter greater than the width of the slot 21, so that in this way the cage member 16a is given a limited amount of angular movement which is sufficient to turn the cage member downwardly slightly beyond the position indicated in Fig. 1 and upwardly to the position indicated in Fig. 8, this latter position being the position where the cage member is turned to when it is desired to release the top rolls 10 in order to exchange the latter, for example.

As is indicated in dot-dash lines in Fig. 1, a set of bottom belts 24 guided by a stationary guide member and the pair of bottom rolls located beneath the top rolls 10 cooperate with the set of top belts 26 which extend about the top rolls 10 and are guided by the front edge of the wall 20a of the cage member 16a. A spring 25 is coiled about the screw member 22 and engages the arm 7 and the wall 20a to urge the cage member 16a downwardly to provide the desired nip between the belts 24 and 26.

With the arrangement described above the projections 15a extend through somewhat more than 180°, and therefore in order to mount the cage member 16a on the saddle member 8a, it is necessary to first hold the cage member 16a in a substantially vertical position in order to place the projections 15a within the cutouts 17a, and then the cage member 16a is turned through approximately 90° to its operating position. The cage member 16a must be turned back through this angle in order to be released from the saddle member 8a, so that with this arrangement a very secure mounting of the cage member is provided. With embodiments where the arcuate projections 15a extend through only 180° or less, it is advisable to pro-

vide stops on the saddle member 8a in order to securely maintain the cage 16a in its operating position. Furthermore, instead of providing releasable screw members 22 for limiting the angular turning of the cage member 16a, fixed bolts or other suitable fastening means may be fixed to the arm 7. It will be noted from Fig. 1 that a stop member 27 regulates the distance between the wall 20a of the cage member 16a and the guide for the bottom belt 24. This stop 27 may be threadedly connected to the wall 20a so that the position of the cage member may be adjusted, or the member 27 may be in the form of a changeable pin.

Fig. 9 shows an arrangement where all of the above described elements are the same, except that the cage member 16b is provided at its intermediate walls with a pair of inwardly extending arcuate projections 15b, and the saddle member 8b is provided with arcuate cutouts in the bottom edges of its side walls into which the projections 15b respectively extend, so that by a comparison of Figs. 7 and 9 it is evident that the embodiment of Fig. 9 is the reverse of Fig. 7 with respect to the guide means for the top belt cage, in that with the embodiment of Fig. 9 it is the cage which is provided with the arcuate projections which are engaged by arcuate surfaces at the bottom edges of the saddle member 8b. Otherwise the embodiment of Fig. 9 is identical with that of Fig. 7.

According to the embodiment of the invention which is shown in Fig. 10, the saddle member 8c is provided at its opposed side walls with a pair of outwardly extending arcuate projections 28 having outer arcuate surfaces which extend about an axis displaced forwardly from the axis of the top rolls 10, as is evident from Fig. 10. With this embodiment cage 16c is provided at its intermediate pair of walls with arcuate cutouts 17 which cooperate with the outer arcuate surfaces of the projections 28, in the manner indicated in Fig. 10. Thus, with the embodiment of Fig. 10 the center of gravity of the cage is displaced forwardly, and as a result a spring similar to the spring 25 described above is unnecessary with the embodiment of Fig. 10, since the weight of the cage itself with this embodiment is sufficient because of its greater moment arm to provide the necessary downward force. Otherwise the embodiment of Fig. 10, since the weight of the cage itself with this embodiment is sufficient because of its greater moment arm to provide the necessary downward force. Otherwise the embodiment of Fig. 10 is the same as that of Figs. 1-8.

Figs. 11-13 show another embodiment of the invention according to which the saddle member 8d is provided with a pair of outwardly extending arcuate projections 15d. The cage for the top belt 16d is provided at its intermediate side walls with arcuate cutouts into which the projections 15d extend in the manner indicated in Fig. 13. Thus, it will be seen that the outer side faces of the projections 15d are covered by the intermediate walls of the cage 16d, and the arcuate surfaces 17d which cooperate with the projections 15d are not located at the bottom edges of the walls of the cage 16d. Instead these walls are provided with shoulders which form the cutouts into which the projections 15d extend in the manner indicated in Fig. 13. The projections 15d and the cutouts into which they extend are of the same length and extend through somewhat less than 180°. With this arrangement, when the cage member 16d is in the operating position indicated in Fig. 11, the cutouts of the cage member into which the projections 15d extend are slightly staggered with respect to the projections 15d and extend beyond the latter in the manner indicated in Fig. 11, so that the intermediate walls of the cage member form an extension of the projections 15d. As is evident from Fig. 11, in the operating position the cutouts and projections 15d together form an arcuate guide of more than 180° for the shaft of the top rolls 10, so that in this position the top rolls are maintained in their operating position by cooperation between the cage member 16d and

the projections 15d of the saddle member 8d. As may be seen from Fig. 12, when the cage member is turned upwardly to a position where the projections 15d register with the cutouts into which they extend, then the shaft of the top rolls 10 is surrounded by less than 180°, and in this position the top rolls can be easily removed. A stop 29 is provided on the wall 20d of the cage 16d to cooperate with the stop 30 fixed to the arm 7, in the manner indicated in Fig. 12, to accurately locate the cage member in the position where the projections 15d register with the cutouts into which they extend. Once the set of top rolls is placed in their operating position, then simply by returning the cage member to the operating position thereof indicated in Fig. 11, the shaft of the top rolls will be retained in its operating position.

It will be understood that each of the elements described above, or two or more together, may also find a useful application in other types of textile drawing mechanisms differing from the types described above.

While the invention has been illustrated and described as embodied in textile drawing mechanisms having guides for a top belt cage, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a textile drawing mechanism, in combination, top roll loading means including a saddle member; a top belt cage member; and guide means formed in part by said saddle member and in part by said cage member for guiding the latter for turning movement with respect to said saddle member about the axis of the top rolls engaged by said saddle member.

2. In a textile drawing mechanism, in combination, top roll loading means including a saddle member having a pair of opposed outer side faces; a top belt cage member having a pair of falls between which said saddle member is located, said faces of said saddle member being respectively parallel to and adjacent said walls; and guide means located at said walls and said faces of said saddle member for guiding said cage member for turning movement with respect to said saddle member about the axis of the top rolls engaged by said saddle member.

3. In a textile drawing mechanism, in combination, top roll loading means including a saddle member; a top belt cage member located next to said saddle member; a pair of arcuate guide portions fixed to and extending from one of said members; and a pair of arcuate surfaces forming part of the other of said members and respectively in sliding engagement with said arcuate guide portions for guiding said cage member for turning movement with respect to said saddle member about the axis of the top rolls which are engaged by said saddle member.

4. In a textile drawing mechanism, in combination, top roll loading means including a saddle member having a pair of opposed side faces; a pair of arcuate guide portions fixed to and extending from said side faces, respectively, of said saddle member and being open at the bottom; and a top belt cage member having a pair of walls formed with arcuate edge portions respectively in sliding engagement with said guide portions fixed to said saddle member so that said cage member is guided for turning movement with respect to said saddle member about the axis of the top rolls engaged by said saddle member.

5. In a textile drawing mechanism, in combination, top

roll loading means including a saddle member having a pair of opposed side faces; a pair of arcuate guide portions fixed to and extending from said side faces, respectively, of said saddle member and being open at the bottom; and a top belt cage member having a pair of walls formed with arcuate edge portions respectively in sliding engagement with said guide portions fixed to said saddle member so that said cage member is guided for turning movement with respect to said saddle member about the axis of the top rolls engaged by said saddle member, said guide portions and said arcuate edge portions of said walls of said cage member extending through approximately 180° about said axis.

6. In a textile drawing mechanism, in combination, top roll loading means including a saddle member; a top belt cage member having a pair of walls between which said saddle member is located; and a pair of arcuate guide portions fixed to said walls of said cage member, extending toward each other, and slidably engaging arcuate portions of said saddle member for guiding said cage member about the axis of the top rolls which cooperate with said saddle member.

7. In a textile drawing mechanism, in combination, top roll loading means including a saddle member having a pair of opposed side faces; a pair of arcuate guide portions fixed to and extending outwardly from said side faces of said saddle member, said guide portions having outer arcuate guide surfaces forming part of a cylinder whose axis is displaced forwardly from the axis of the top rolls which cooperate with said saddle member; and a top belt cage member having a pair of walls between which said saddle member is located formed respectively with arcuate edge portions which respectively are in sliding engagement with said outer arcuate surfaces of said guide portions, whereby said cage member is turnable with respect to said saddle member about an axis displaced forwardly from the axis of the top rolls which cooperate with said saddle member and whereby said cage member is guided for turning movement with respect to said saddle member.

8. In a textile drawing mechanism, in combination, top roll loading means including an arm and a saddle member fixed to and extending downwardly from said arm; top belt cage means cooperating with the top rolls which cooperate with the saddle member; guide means formed in part by said top roll cage means and in part by said saddle member for guiding said top belt cage means for turning about said saddle member; and means fixed to said arm for limiting the turning movement of said cage means.

9. In a textile drawing mechanism, in combination, top roll loading means including an arm and a saddle member fixed to and extending downwardly from said arm; top belt cage means cooperating with the top rolls which cooperate with the saddle member; guide means formed in part by said top roll cage means and in part by said saddle member for guiding said top belt cage means for turning about said saddle member; and means fixed to said arm for limiting the turning movement of said cage means, said limiting means being in the form of a wall portion of said cage means formed with a cutout and an elongated member fixed to said arm, extending downwardly and freely through said cutout, and having an enlarged bottom head end of a size larger than the width of said cutout located beneath said wall portion of said cage means.

10. In a textile drawing mechanism, in combination, top roll loading means including a saddle portion adapted to cooperate with top rolls having a predetermined axis; top belt cage means cooperating with said saddle portion; and guide means formed in part by said top belt cage means and in part by said saddle portion for guiding said cage means for turning movement with respect to said saddle portion substantially about said axis.

11. In a textile drawing mechanism, in combination, top roll loading means including a saddle member having a pair of opposed side wall portions; a top belt cage member having a pair of wall portions between and adjacent which said wall portions of said saddle member are located, one of said pair of wall portions being formed respectively with a pair of arcuate cutouts and the other of the pair of wall portions being respectively provided with a pair of arcuate extensions extending into and substantially filling said cutouts, respectively, so that said saddle member and cage member are turnable with respect to each other substantially about the axis of the top rolls engaged by said saddle member, said cage member being turnable with respect to said saddle member from a position where said arcuate projections and arcuate cutouts are located in the same angular position to a position where said cutouts extend beyond said arcuate extensions and the portions of said walls formed with said cutouts and extensions extend through more than 180° , so that a shaft of the top rolls which cooperate with said saddle member will be held in position by said saddle member and said cage member.

12. In a textile drawing mechanism, in combination, top roll loading means including a saddle member having a pair of opposed side wall portions; a top belt cage member having a pair of wall portions between and adjacent which said wall portions of said saddle member are located, one of said pair of wall portions being formed respectively with a pair of arcuate cutouts and the other of the pair of wall portions being respectively provided with a pair of arcuate extensions extending into and substantially filling said cutouts, respectively, so that said saddle member and cage member are turnable with respect to each other substantially about the axis of the top rolls engaged by said saddle member, said cage member being turnable with respect to said saddle member from a position where said arcuate projections and arcuate cutouts are located in the same angular position to a position where said cutouts extend beyond said arcuate extensions and the portions of said walls formed with said cutouts and extensions extend through more than

180°, so that a shaft of the top rolls which cooperate with said saddle member will be held in position by said saddle member and said cage member; and stop means cooperating with said cage member for positioning the latter, in a release position where said arcuate projections and cutouts are in register with each other, respectively.

13. In a textile drawing mechanism, in combination, top roll loading means including a saddle member having a pair of opposite downwardly directed arcuate portions 10 provided with outwardly extending arcuate projections; and a top belt cage member having a pair of wall portions formed with lower arcuate edge portions having arcuate cutouts, respectively, into which said projections slidably extend, said wall of said cage member covering the outer side faces of said projections and said projections and cutouts being movable from a position where they register with each other to a position where they extend beyond each other to more than 180° .

14. In a textile drawing mechanism, in combination, 20 top roll loading means including an arm which extends in a direction substantially parallel to the drawing plane in the operating position of the top roll loading means and a saddle portion having a pair of opposed side walls extending downwardly from said arm and formed with a pair of arcuate cutouts at the lower edge of said saddle portion walls; a top belt cage member having a pair of walls between and adjacent which said saddle portion walls are located, said cage walls also having arcuate cutouts formed in their bottom edges, respectively; and 25 guide means located at all of said walls at said arcuate cutouts thereof for guiding said cage member for turning movement with respect to said saddle portion substantially about the axis of the top rolls which cooperate with the saddle portion.
